UNITED STATES PATENT OFFICE

GUSTAV A. BOETTCHER, OF JAMAICA, NEW YORK, ASSIGNOR TO MULTI-NEEDLE ENGINEERING CORPORATION, OF NEW YORK, N. Y.

BRAIDING DEVICE

Application filed February 3, 1938. Serial No. 85,722.

This invention relates to multineedle sewing and quilting machines, and more particularly to attachments for the same adapting the machines to perform more elaborate and valuable work without increasing or changing the operations normally performed by the regular equipment of said machines.

The main object of my invention is therefore, to provide quilting or sewing machines with a device adapted to place an ornamental accessory such as a cord, braid, ribbon or similar object in the path of the needles of said machines when a strip of fabric is being stitched by the machines, whereby the needles will securely sew or fasten said ornamental accessory to said fabric while following the predetermined paths of their respective designs.

It is also an object of my invention to provide machines of this class with a finger bar which is arranged to move solely in horizontal planes through a smoothly curved path which avoids sharp changes in direction and therefore may run very smoothly at a high speed without undue vibration or noise. This allows of increased output for such machines and greatly enhances their efficiency.

Other objects and resulting advantages will appear hereinafter as this specification proceeds.

In the accompanying drawing,

Fig. 1 is a view of the main portion of a quilting machine equipped with an attachment made according to my invention and embodying the same, the central portion of the machine being cut out to allow of clearer illustration.

Fig. 2 is a side view of the same on line 35-35 in Fig. 1.

Fig. 3 is a similar view with only the most essential operative parts shown, being now in more advanced position.

Fig. 4 is a plan view of a section of the finger bar 8 of the previous views in operative position.

Fig. 5 is a view of a fabric with a braid or similar accessory as it appears when run through the machine.

Fig. 6 is a plan view of a finger of the machine in one extreme operative position rela-

tive to an adjacent needle, and a series of successive positions indicated in dotted outlines.

Fig. 7 is a left end view of the gear and cam transmission located at the extreme right in Fig. 1.

Fig. 8 is a top view of the same transmission.

Throughout the views, the same reference numerals indicate the same or duplicate parts.

In the operation of sewing and quilting machines of the class mentioned, fabrics are often encountered which are possessed of such a texture that the thread of the machine needles becomes so deeply worked into the fabric surface that the latter becomes somewhat depressed, which results in practically concealing the thread. But if the thread is caused to contract upon and secure a cord or a braid to the fabric surface, the design which the needles may be following will immediately become more apparent, as the cord will be easily visible.

In order to accomplish this desirable result, I may use a quilting machine which includes a pair of spaced corresponding frame members 1-1, and a pair of tie rods 2-2 securing the frames together. Upon these rods a pair of similar needle plunger blocks 3-3 are rigidly mounted, and between them a pair of presser plunger blocks are secured at 4-4. In each of the needle plunger blocks a plunger 11 is slidably mounted, the two plungers shown being secured at their lower extremities to a needle bar 12 to support the latter and whereby the bar may be raised and lowered. Similarly, a plunger 14 is movably mounted in each of the blocks 4-4 and is secured at the lower extremity to a presser foot or bar 15. The actual means for raising and lowering these two sets of plungers have been omitted as being too well known, and, moreover form no part of the present invention.

Likewise, the supporting and moving means for the fabric table 50 has been omitted for the same reasons, the table and a fragment of a fabric at 44 being, despite the omissions located in proper relative positions to the machine.

However, the novel and useful features of my invention are carried out by mounting a

pair of similar pinion arms 5—5 on aforesaid rods 2—2 of the machine. On each of these arms, a pair of oppositely disposed gib plates 6 and 10 are secured to furnish bearings for a pinion shaft 47 while housing the pinions 7—7 which are mounted on said shaft. Furthermore, the plates also guide and support a pair of similar racks 9—9, comprising as it were corresponding tracks for said racks 10 each of which is in mesh with its respective adjacent pinion and is enlarged at the rear extremity into a slotted block 30. The rack blocks, as they may be termed, are adapted to slidably support a finger bar 8, and, as the 15 racks are controlled by the same shaft, they will move together when the shaft and pinions are rotated and will therefore move said bar uniformly along its entire length.

The finger bar has a series of transverse 20 grooves 48—48 in which a row of fingers rest, while a block 31 is screwed upon the bar upon each of the fingers to retain the same. Each finger is adapted to normally project over the presser foot 15 and terminates in a double eye 25 or head 32, one of these apertures being noted as 33 and the other noted 34. The apertures may be of different sizes, or, as in the case of the finger 51 the head 52 has a single large aperture or slot which may accommodate a 30 ribbon or wide braid.

As is usual in machines of this class, the bar 12 is provided with a series of needles as indicated at 13. If a piece of fabric 44 is placed under the needles as in the first three views, 35 the needle especially shown in action is furnished with an ordinary thread 45, while the ornamental cord 42 is first passed through an eye 43 on the finger bar, thence into the eye in the finger head 32. Both the cord and 40 thread pass down through the needle aperture 49 in the presser foot to the fabric beneath where the thread meshes the cord to the fabric.

The relative positions and possible movements of the fingers with respect to their adjacent needles are entirely novel, as the fingers and the bar 8 upon which they are set may be advanced to a point where the fingers will project beyond the needles first on one 50 side, then withdrawn, the bar slid slightly through rack blocks 30—30 and the fingers again advanced beyond the needles on the other side. This is, in effect, a semi-circular or horse-shoe movement of the finger heads 55 about their respective needles constituting a movement of less than 360°. In the sixth view, this is directly indicated by a plan view of the movement of a portion of a finger 16—32. In the first and lowest position, the 60 finger is advanced to the extreme position on the near side of needle 13, while at 36 and 37 the finger is more and more withdrawn while also beginning to be shifted to the other side. At 38 and 39 the finger is shifted more yet, 65 while at 40 it is still more shifted while

being again advanced. Finally at 41 the extreme advanced position on the far side has been attained. When this position has been reached, the movement of the finger is reversed and is returned to the first position through the successive stages 40, 39, 38, 37 and 36, when another change in movement is again effected. Thus, the finger is normally adapted to reciprocate in a practically semi-circular path about the needle. The practical effect of this movement will presently be noted when the means by which it is accomplished is described.

The pinion shaft 47 is furnished with a lever arm 17 at one extremity, while a short rod 18 is secured to the free extremity and adapted to extend beyond the adjacent frame 1. And beyond this frame is located a transmission frame 22 which is provided with a horizontal shaft 27. This shaft has a gear 29 mounted on one extremity by which to drive the apparatus and which may be engaged by a gear mounted on the main shaft of the machine or on a motor or by any other motive means. Or the gear may be replaced by a pulley and driven by a belt. Within the frame 22 a bevel gear is secured on the shaft, while at the inner extremity an eccentric cam is mounted. In the upper portion of the transmission frame, a second bevel gear is suspended at 26 which is engaged by the first bevel gear 28, and a second cam 25 is mounted above the transmission frame and is controlled by gear 26. A yoke or a ring 20 is mounted on the periphery of the first cam 21, while a bar 19 is secured to the yoke. The upper extremity of the bar is connected to the lever pin 18, and rotation of the cam 21 will thus raise and lower yoke 20, bar 19 and through pin 18 move lever arm 17, and thereby partly rotate the pinion shaft 47 in reciprocal manner.

As has been already stated, rotation of the shaft 47 will advance or withdraw the finger bar with its series of fingers from between the needles, according to the direction of rotation. In similar manner, a cam yoke 24 is mounted on the cam 25 and is movable thereby. Naturally, this cam moves simultaneously with the former cam, although their yokes may have entirely different movements according to their difference in timing and relative form. The finger bar 8 is connected to yoke 24 by a link 23, which permits the yoke to directly reciprocate the bar according to the movement imparted by cam or eccentric 25, the bar being, of course, slidably in the blocks 30—30 as mentioned. This will afford a side movement to the fingers and, if the cams are relatively so timed that first cam 21 causes an advance of the fingers to the right side of the adjacent needles, and then a withdrawal of the same, then cam 25 will cause a lateral movement toward the other side. Then cam 21 will cause an advance of the 100

fingers on the far side of the needles. Continuous rotation of the transmission will indefinitely produce these movements so that each finger will have, as it were, a horse-shoe 5 movement about its adjacent needle.

Of course, the movements of the fingers just described must bear a direct relation to the movements of the needles with which they cooperate, but the motive elements of the needle plungers are known, and do not form any 10 part of this invention, it being sufficient to construct and time the herein described transmission in agreement with the movements of the needles and presser foot.

If now a piece of fabric, such as quilting, felt or any article of like nature is introduced beneath the presser foot at 44, a thread 15 may be passed through the needle from a spool or similar source down through the 20 aperture in the presser foot to the fabric, and is formed into stitches by any known stitch forming mechanism which is in the present instance omitted and merely represented by a curved support table or apron 50. The 25 cord or braid passes through the finger block eyes 43—43 from a convenient source of supply and thence through the eye of the finger, and, finally down through the aperture of the presser foot to the fabric to which it is secured 30 by the thread of the needle. As the needle is raised, the finger with its braid moves around the needle position to lay the cord in the path of the next stitch. This operation is repeated 35 each time the needle descends to form a stitch, the result being similar to 46 as shown in the fifth view.

It is clear that the finger bar by moving through curved paths back and forth, thereby avoids sharp or sudden changes in the 40 direction of its movement except at the extreme positions, and hence eliminates vibration and noise that would result if the bar should intermediately pass around corners through angular paths of movement. There 45 is also an advantage attained by moving the bar in practically only horizontal planes, for the added problem of contending with the force of gravity when moving in vertical or high pitched planes is also avoided. However, in view of the fact that the movement is 50 always a smooth curve for the finger bar, the latter may be swung around such a path at a considerably greater speed than if its path were a triangle, a rectangle or required any 55 angular movement differing from the horse-shoe path which I have discovered to be practically ideal for this purpose. It is also an added advantage that the curved path about 60 the needle eliminates thread breakage.

Of course, I may use any design or figure for the fabric, as desired, and may also pass two or more cords through each finger or alternate fingers to be stitched to the fabric in 65 the machine, these points merely illustrating

the novelty and useful versatility of my invention.

Having now fully described my invention, I claim:—

1. In a multi-needle sewing machine having a fabric support and a series of needles with means for supporting the same, a braiding attachment including a pair of arms secured to said machine and provided with a pair of corresponding racks, each of said racks terminating at one extremity in the form of a block, a transverse bar slidably mounted in said blocks and provided with a series of braid guides, and means to reciprocally move said bar and said racks including 70 a pinion arranged upon each arm in mesh with the adjacent rack.

2. In a multi-needle sewing machine having a fabric support and a needle support provided with a series of needles, a pair of arms mounted upon said machine and a pinion rotatably supported upon each arm, a rack slidably mounted upon each arm and meshing with the respective pinion supported upon 75 said arm, a shaft connecting said pinions to synchronize the same, a bar slidably mounted upon said racks and provided with a plurality of braid fingers, means to partly rotate said shaft and means to slide said bar reciprocally along its axis.

3. In a multi-needle sewing machine having a fabric support and supporting means for a plurality of needles, a plurality of supporting arms arranged upon said machine, 80 slideable racks individually mounted upon 100 said arms in relative parallelism with respect to each other, a pinion upon each arm in mesh with the respective rack located thereon, a shaft connecting said pinions and having a lever on one extremity thereof, and means for actuating said lever and said racks including a transmission having a frame, a cam supported thereon, a yoke upon said cam, and a link connecting said yoke to said lever.

4. In a multi-needle sewing machine having a fabric support, a pair of arms upon said machine, a pinion rotatably mounted upon each arm, a rack slidably supported upon each of said arms in mesh with the respective pinion thereof, a bar movably supported upon said racks, and means to move 105 said racks and said bar.

5. In a multi-needle sewing machine provided with a fabric support and a frame for said machine, a needle support upon said machine, a pair of arms rigidly secured to the frame thereof, a pair of slideable racks mounted on said arms in relative parallelism, a pinion rotatably supported upon each arm in mesh with the rack upon said arm, a shaft connecting said pinions and provided with a lever, a finger bar slidably supported upon said racks and arranged to move along its length, and means to partially rotate said shaft and move said bar, including a pair of 110 115 120 125 130

cams, a link connecting one of said cams to said finger bar and a yoke providing the connection between said link and said cam, a second yoke upon the other cam and a link associated with said second yoke and connected to said shaft lever.

6. The combination in a multi-needle sewing machine, of a frame and a needle support, an arm secured upon said frame, a guide track mounted upon said arm in a transverse position relative to said needle support, a rack slidably arranged in said track and provided with a slotted block, a pinion also mounted upon said arm in mesh with said rack and provided with a shaft, a lever upon said pinion shaft, a bar slidably supported in said slotted block, means to slide said bar and means to actuate said lever, including a link connected to said bar, a second link connected to said lever and means to actuate said links.

7. A multi-needle sewing machine including a frame, a needle support, an arm having a guide track thereon and projecting rigidly from said frame, a rack slidably mounted on said track and provided with a bearing block upon one extremity thereof, a finger bar slidably supported in said block and projecting therethrough, a pinion meshing with said rack and provided with a shaft rotatably supported upon said arm, a lever fast upon said shaft, and means for actuating said pinion and rack and said finger bar including a pair of cams mounted at an angle to each other, a yoke upon one cam connected to said finger bar by means of a link, and a second yoke upon the other cam connected by means of a second link to said pinion shaft lever.

8. The combination with a multi-needle sewing machine having a fabric support, means for supporting a plurality of needles, a slideable finger bar, and an independently slideable member arranged to move in relatively horizontal planes and supporting said finger bar, of means for sliding said finger bar and actuating said independently slideable member in solely horizontal planes, there being a plurality of braid fingers mounted on said finger bar, said sliding and actuating means being arranged to shift said fingers about said needles in smoothly curved paths to avoid vibration and permit high speed operation of said machine as a whole.

9. The combination with multi-needle sewing machine having a fabric support, means for supporting a plurality of needles, a slideable finger bar having a plurality of projecting fingers arranged thereon, and a moveable support for said finger bar, of means for so moving said finger bar support and actuating said finger bar solely in horizontal planes as to shift said fingers about said needles reciprocally in smoothly arcuate paths in order to eliminate vibration of the

machine intermediate the extremities of said arcuate paths and reciprocations of said fingers.

10. The combination in a multi-needle sewing machine having a fabric support, means for supporting a plurality of needles, and a movable finger bar having a plurality of fingers thereon, of means for solely actuating said finger bar in a relatively horizontal plane in such manner as to move said fingers through smoothly curved arcs about said needles in reciprocal fashion, whereby to reduce vibration of the machine as a whole and permit running the same at a relatively high speed.

11. The combination in a multi-needle sewing machine having a fabric support, means for supporting a plurality of needles, and a movable finger bar provided with a plurality of braid fingers thereon, of means for actuating and guiding said finger bar in such manner as to shift said fingers reciprocally about said needles through smoothly curved paths for the purpose of reducing vibration of the machine and permitting the same to be operated at a relatively high speed, as well as avoiding strain on the threads of the machine associated with said needles.

In testimony whereof, I have signed my name to this specification this first day of February, 1926.

GUSTAV A. BOETTCHER.
